CONCRETE PILES AND PILING ELEMENTS.

1,088,946.

Specification of Letters Patent.

Patented Mar. 3, 1914.

Original application filed July 23, 1909, Serial No. 509,111. Divided and this application filed April 23, 1913. Serial No. 763,077.

To all whom it may concern:

Be it known that I, MAXWELL M. UPSON, a citizen of the United States, residing at Englewood, in the county of Bergen and State of New Jersey, have invented certain new and useful Improvements in Concrete Piles and Piling Elements, of which the following is a full, clear, and exact description.

This is a division of application Ser. No. 10 509,111, filed July 23, 1909.

The invention relates to concrete piling and piling elements for foundations, walls, cribs, coffer-dams, piers, wharves, bridges, bulkheads, buildings and the like.

15 The object of the invention is a practical construction, physically and economically, of said nature for such purposes, and the invention consists of the structures hereinafter disclosed and claimed.

20 Of the drawings, Figure 1 is a horizontal section (at 1, 1, Fig. 2) of a plurality of concrete piles or piling elements constructed in accordance with the invention and combined to form piling; Fig. 2 is a partial elevation of the same, and Fig. 3 is a horizontal section on line B—B of Fig. 2. Fig. 4 is a similar section, but showing a modification.

25 The concrete piles shown may consist of the material commonly used, *i. e.*, comprising cement, sand, and broken stone or gravel, the last being preferably used for economy. The piles may be molded in any known way, and may, and preferably do, contain the usual 30 vertical steel reinforcing rods or equivalents shown at Y, as mutually supported by wires or stirrups X, in the usual way. The concrete of the piles is indicated in Fig. 1 in section by the cross-hatching. Contribution to 35 the steel reinforcement of the piling elements is made by the steel interlocks herein-after described, which may be molded in the concrete at the same time as the ordinary reinforcing rods above mentioned, the interlocks being preferably engaged with the supporting stirrups of the vertical reinforcing rods as shown.

40 The chief characteristic of my combination of metal interlock with a concrete pile is that the interlocks need be placed only where it is desired that they perform their locking function, thus saving cost; the piling essentially consisting chiefly of the concrete piles; and also that the interlock is so

combined with the concrete of the pile itself 55 as to permit the same to be so made of concrete in the ordinary way except in so far as concerns the embedding or reception of the metal interlock itself and also such modifications of the interlocking face of the pile 60 as may result from such embedding or adaptation for reception, or as may be necessary to permit the interlock to discharge its function. This invention makes it possible to use as a piling element the ordinary concrete pile, without any external covering or container and capable of being grounded in the manner usual in the case of concrete piles.

55 I have found that a concrete wall or piling made up of the piles of this invention, is substantially even stronger and more rigid than a continuously molded wall of concrete 65 would be. The advantage in installation of this substitute for a continuously molded 70 wall, will be clear from a consideration of the fact that the piles of this invention are manufactured as separate individual units, either in or out of their grounded positions, but preferably out, and before grounding; 75 and when so pre-molded they can be readily handled, and grounded in the ordinary way in which concrete piles are sunk, as by water-jetting or driving, or both, and without the necessity of the preliminary trench 80 excavation required for a continuously-molded concrete wall.

85 The construction and molded location of the metallic interlocks, which may be, and in many cases preferably are, of rolled steel of 90 any shape suitable for interlocking, will be understood from a consideration of such members as A, B and B', for example at the left of Fig. 1. These members preferably do not extend continuously in the horizontal 95 line of piling through the molded concrete pile, (see Fig. 2 also) but have only sufficient shanks S, S, to cause sufficiently strong embedding in the mass of concrete of the pile and to provide lateral bearing surface 100 against the concrete to resist strains tending to displace them laterally, such strains, for example as would shear off the simple integral concrete tongue C, or the walls D, D, of the groove for said tongue, if the metal 105 interlocks were not molded in as stated. The concrete tongue C, and groove M, (walls D, D') are used, if desired (in addition to

the principal features of the invention) for the purpose of assisting in closing the joint between the piling elements while permitting the presence of the vertically-short interlocks A, B, to be described. Other means 5 for closing the joint to be described may be used if desired, with or without the simple integrally cast concrete tongue and groove. The metal interlocks are suspended in the 10 mold in any way customary with ordinary reinforces. In the lack of a steel web integrally connecting A and B in a single pile or piling element, this lack being one feature of substantial economy, other and cheaper 15 means may be employed as hereinafter described, if desired, to increase resistance to strains tending to pull the interlocks out of the concrete; an important object of the interlocks being to cause the pile to resist 20 strains at right angles to its vertical length, including those in line with the piling as well as those transverse to it, when desired, or either, if desired. Thus A and B may have one or more lateral projections on their 25 inner ends as indicated at E, E; or tie-rods F (Figs. 1 and 2) may connect A B. Other such means are also disclosed and will be described. In cases, however, where it is necessary only to provide against transverse 30 strains the metallic interlock need not be double in the sense that it also resists longitudinal strains in the line of the piling. The metal interlocks may be used as guides for successively grounding adjacent piles, 35 (the vertically disposed sections to be described being in vertical alinement for this purpose); so that when one piling element is in place in the ground, the next is lifted in place so that the interlock registers, the sec- 40 ond pile being then sunk alongside the first. After the grounding of the two adjacent piles, the free space at the joint in the vicinity of the interlock may be filled with hydraulic cement termed grout (indicated by 45 dots in Fig. 1), and consisting of cement, sand and water in customary proportions, lacking the broken stone forming a constituent of the concrete of the piles themselves. This grout sets with the two ad- 50 joining concrete piles, closes the joint water- proof to make a substantially continuous wall of molded concrete, and also surrounds the metal interlock with the result of pro- 55 tecting it from rust or corrosion by the ac- tion of salt water. By forcing the grout down into the bottom of said space, if de- sired, the pile-footing can be improved so as to increase the carrying capacity of the 60 grounded structure. The grouting of the joint, or of the concrete tongue-and groove construction C, M, or both, permits one of the preferred constructions as shown in Figs. 1, 2, 3 and 4. The section B—B of Fig. 2 (Figs. 3 and 4) shows a case where hook- 65 interlock A does not extend beyond the face of the molded concrete pile. In Fig. 3 is shown a permanent thin sheet-steel hollow member G, which serves not only as the mold-core for a passage H, extending from end to end of the concrete pile and opening 70 through the hollow of hook-interlocks A, but serves also as a wearing-guide for the co-operating member B¹, or B to reinforce the wall of the passage in the concrete pile. This hollow steel core G may be bent as a 75 core for the mold to form a hole in the concrete between the relatively vertically disposed metallic interlocking members, as shown in Fig. 3, said hole having the same 80 diameters as that of the inside of the hook-portion of member A, shown in the hollow core G, or may be larger than the inside of the hook portion, as indicated by G¹, Fig. 4, so that the wall of the hole H¹, between A, A, sets back of the inside of the hook portion 85 of A. In the latter case hook-portions A will take all the wear, and core G¹ may be removed after the molding of the pile, if not desired as a permanent reinforce for the passage-wall. Before removal, however, it has 90 served the purposes of producing a passage H, in perfect alinement with the hooked portions of A, and of supporting said hook members during the process of casting the concrete pile. The vertical spaces, passages 95 or grooves between the vertically disposed hook members A, may be cored to any other desired shape, if desired.

The number of vertical interlocks A, one or more, and the vertical length of each, the longitudinal width of the shank S, if used; and the dimensions of shank-end interlock F, if used, are matters of practice determined in each case by calculations as to the 100 pull and strains to which any particular installation of piling will be subjected during and after installation. The same is true as to the other interlocks B¹, corresponding with members A, because vertically successive members B¹ will be guided into their 105 appropriate co-operating members A, on account of the alinement established by the substantially extended vertical engagement of the first vertical pair. It is clear that after the grouting described above, in the 110 space around the interlock, the joint is as watertight as if the metal interlock were vertically continuous from top to bottom, and it is clear also that substantial economy 115 of steel results from the molding of the concrete of the pile into the vertical and horizontal spaces between the interlocks. (In Fig. 2 such concrete is shown above and below, and between the metallic interlocks.) The steel members A, B, B¹ (molded in 120 the piling elements) on the other hand, provide interlocking means capable of withstanding strains not possible to be born by interlocks consisting of simple integral concrete portions of the piles. Finally, the 125

piling itself is not only substantially as strong as sheet-steel piling, but provides that increased stability and carrying capacity which could be furnished otherwise only by a continuously molded concrete wall or by sheet steel piling plastered thickly on both sides with concrete. The vertical or horizontal separation of the interlocking members or both, permits the casting of a homogeneous reinforced concrete pile which is much stronger than a pile in which the interlocking members extend throughout the whole length or width and sever it into two parts. In other words, it permits the pile to be made integrally of concrete as distinguished from a mere plastering of concrete over an ordinary sheet steel pile.

Many modifications may be employed. A and B are shown as molded in concrete tongue C, and groove M respectively; but they might be reversed. They are shown as extending only to the face of the pile, but they might extend beyond it, as at J, K, and L. Each pile may have two grooves, N, O, instead of one groove M and a tongue C; and the larger space afforded by resulting adjoining grooves M¹, N is useful in most readily permitting a thorough grouting or even concrete filling in of the joint and metal interlocks. Or the pile may have flat joint-faces, a hook interlock J¹ being entirely embedded in the concrete of the pile, and an interlock K, having only its shank S, embedded, its bill projecting beyond the flat face. Or ordinary steel channels P, Q, R may be embedded (as partial equivalents of hooks A), one, as P or R, extending only to a joint face of a groove pile, and the other, as Q, extending beyond the opposite grooved face, and both Q and R coöperating together in a large grouting space T formed by grooves in adjacent pile-faces. The grooves in the piles, which grooves contain the interlocks, such as the space V, are cored in practice by means of their sheet steel forms bent to shape, such as U, in order to avoid the expense of first shaping solid cores. These hollow or thin sheet metal cores, as U, may be left in place to serve as wearing guides for the interlocks, particularly such as K or L which engage with only one edge of their respective coöperating members P or R.

In some cases a pile can be molded with only one metal interlocking member, as for example the I beam shown at W, so that this single member, molded in one of the piling elements, can be engaged in a groove in the joint face of another piling element. The I beam is lodged in a cavity formed by the thin metal core or reinforce U¹. Such cases are where the thicknesses of the concrete pile and of the groove-walls D¹, D² are sufficient, and the interlocking groove and member W are sufficiently narrow, so that

the walls or projections D¹, D² will not be sheared off by transverse strains. In such cases the effect is as if each of both adjoining joint-faces of adjacent piles had its own separate metallic interlock molded in it, and as if the two interlocks engaged each other. But in the disclosure, this single interlocking member requires much less of the expensive material (as rolled steel) than when each pile has two interlocking members, one for each joint-face, as A, B. This construction at W is practicable as compared with an all-concrete interlock, on account of the great strength of the small mass of steel, which small mass also permits a large and strong mass of concrete at D¹, D². Whenever necessary or desirable the concrete portions D¹, D² may be strengthened by molded-in steel reinforcing members such as Z, Z¹. In this particular embodiment of the invention, very great economy of steel can be had even if the steel member extends uninterruptedly from top to bottom of the pile. If the reinforces Z, Z¹ be used, they may be simply the ordinary wires or stirrups.

In order to save the cost of grout for filling the interlocking spaces and protecting the metallic interlocks, the stirrups, or other metallic reinforcements may be extended, in molding, as at X¹, beyond the flat face of the pile, and the mold be constructed so that the broken-stone mixture will entirely surround the interlocking members to form the strong and rigid interlocking projection K¹ engaging in the groove T¹ in the adjacent pile. The walls of the groove T¹ are in this case preferably reinforced by molded-in metallic members, as Z². Another way of avoiding expensive grouting, and at the same time to obtain metallic interlocking of grooved concrete piles, is to prepare an independent locking member consisting of a concrete column having the sheet metal envelop A¹ of double-wedge form to coöperate in the correspondingly formed pile groove A². If desired, this member A¹ may be cast integrally with a piling element, as the one shown at its right, and in such case the groove-reinforce Z² may be omitted from that pile, as shown. When not cast with a piling element, member A¹ may be driven into the ground in one pile to serve as a guide for the grounding of the adjacent pile.

In case a grounding guide is not necessary, an interlock such as the hollow metal form C¹, of the double-wedge form shown, may be placed in the edge of the pile grooves, and then grout may be applied both inside and outside of the hollow form, the reinforcements Z³, Z⁴ being employed to strengthen the pile grooves.

Except for convenience in locating the vertically-disposed interlock sections in their proper vertical positions, it is not absolutely necessary that the lefthand side of sections

W be pre-molded in the pile, and they might be lowered, after the grounding of the pile, into a groove molded therein; although in such case W may be subsequently grouted in 5 the groove, either before or after the successive grooved pile has been grounded along W as a guide.

What I claim is:

1. A piling element comprising a pile 10 composed of concrete and having a grouting groove in one face, and having embedded in one face a metallic strain-resisting member to engage an adjacent piling element.
2. A piling element comprising a pile 15 composed of concrete and having vertical grouting spaces in two vertical faces and having embedded in at least one of said faces a metallic strain-resisting member to engage an adjacent piling element.
3. A piling element comprising a pile 20 composed of concrete and having embedded in it at one vertical face, a metallic interlocking member having its interlocking portion projecting beyond said face.
4. A piling element comprising a pile 25 composed of concrete and having a metallic member vertically disposed and permanently incorporated inside it to serve as an interlock with an adjacent piling element.
5. A piling element comprising a pile 30 composed of concrete and containing a metallic guiding member arranged to resist lateral strains and to engage with and guide an adjacent pile to a grounded position.
6. A piling element consisting of a pre-molded pile composed essentially of concrete 35 and having embedded in it a metallic member adapted for engagement with a succeeding piling element to resist strains at right angles to the vertical length of the pile.
7. Piling comprising successive piles composed of concrete and joined together by metallic interlocks held inside the respective piles.
8. Piling comprising successive piles composed of concrete and connected by a metallic interlocking vertical guide held inside 45 the respective piles.

9. Piling comprising successive piles composed of concrete and joined together by a 5 metallic interlock embedded in the concrete of at least one of the piles.

10. Piling comprising piles composed essentially of concrete and arranged in succession to form the piling, and metallic means 5 supported by the piling and extending from one pile to a point beyond the facing side of the next pile, to prevent displacement of the latter in a direction transverse to the line of the piling.

11. Piling comprising piles composed essentially of concrete and arranged in succession to form the piling, and metallic means for each pair of adjacent piles, each such means being secured to both of its adjacent 6 piles, substantially rigidly in the line of the piling, to prevent material separation of the piles from each other in the line of the piling.

12. Piling comprising piles composed 70 essentially of concrete and arranged in succession to form the piling, and metallic means substantially rigidly secured to both of two adjacent piles, in directions transverse to and in the line of the piling, to prevent material displacement of the individual piles in any horizontal direction.

13. Piling comprising successive piles composed of concrete, and a metallic member 75 extending from inside the concrete of one pile to the inside of the concrete of the next pile.

14. Piling comprising successive piles composed of concrete, one having an embedded metallic interlocking member, and 80 the other an interlocking cavity to receive the metallic member.

15. Piling comprising successive piles composed of concrete held together by metallic interlocking members.

In testimony whereof I affix my signature in the presence of two subscribing witnesses.

MAXWELL M. UPSON.
